C. H. FISCHER.
ELECTRIC LAMP.
APPLICATION FILED MAR. 13, 1915.

1,140,894.

Patented May 25, 1915.

UNITED STATES PATENT OFFICE.

CHARLES HARRY FISCHER, OF CINCINNATI, OHIO.

ELECTRIC LAMP.

1,140,894.

Specification of Letters Patent. Patented May 25, 1915.

Application filed March 13, 1915. Serial No. 14,215.

To all whom it may concern:

Be it known that I, CHARLES H. FISCHER, a citizen of the United States, residing at Cincinnati, in the county of Hamilton and 5 State of Ohio, have invented certain new and useful Improvements in Electric Lamps, of which the following is a specification.

My invention relates to electric lamps especially adapted to be employed as head-lights on automobiles or other vehicles, and 10 has for its object the provision of novel means whereby to focus the electric light-bulb from the outside or from the inside of the lamp body, and for maintaining the 15 bulb in adjusted position.

It is the object of my invention further to provide novel means for manually shifting the light-bulb with relation to the reflector by rotative or axial or combined 20 rotative and axial movements, so as to position the light-bulb in or out of the focus of the reflector as may be desired; further to provide novel coacting means for maintaining the light-bulb in adjusted positions; further 25 to provide novel means in the space between the casing and reflector for holding the socket-member coacting with the plug of the light-bulb and with the plug of the electric connection against rotation during the 30 attachment of these plugs to the socket-member, whereby the axial movement of the socket-member is limited and the rotative movement thereof is prevented during such attaching.

35 My present invention is an improvement on the device shown, described and claimed in my Patent No. 1,114,976, dated October 27, 1914.

I do not herein broadly claim the complementary means for maintaining the socket-member in adjusted positions, having shown, 40 described and claimed the same in an application for Letters Patent on improvements in electric lamps, executed of even date herein- 45 with, and being Serial No. 14,214, and filed in the United States Patent Office on the 13th day of March, 1915.

The invention will be further readily understood from the following description and 50 claims, and from the drawings, in which latter:

Figure 1 is an axial section of an electric lamp embodying my invention. Fig. 2 is a perspective view showing the means for at-

taching and focusing the electric light-bulb 55 and for attaching the connector-plug, the parts being shown in separated relation. Fig. 3 is a side elevation of my improved device in assembled relation, the reflector and casing being partly broken away. Fig. 4 is 60 a similar view, showing the socket-member in rear position with its stop received in one of the recesses in the flange. Fig. 5 is a front elevation of my improved device with the casing partly broken away and the reflector 65 and light-bulb removed. Fig. 6 is a rear elevation of my improved device, with the reflector partly broken away and the casing and connector-plug removed. Fig. 7 is an axial section of my improved device, partly 70 broken away, taken on a line corresponding to the line 7—7 of Fig. 5, the socket-member being shown in forward position with its limiting stop in frictional contact with the wall of the reflector-opening. Fig. 8 is a 75 cross-section of my improved device taken on the line 8—8 of Fig. 3. Fig. 9 is a perspective view of the spring-member showing the contact-surface of its shoe; and, Fig. 10 is an enlarged cross-sectional detail of the 80 socket-member.

I do not herein claim the means for supporting and insulating the central electric terminal post of the electric connector, having shown, described and claimed the same 85 in an application for patent on electric connectors, filed July 17, 1914, Serial No. 851,581.

The casing of the lamp is shown at 11, and the reflector at 12. The reflector is exemplified as a parabolic reflector secured to the casing by screws 13 for forming the body of the lamp as a double-walled body between the walls of which there is the 90 space 14.

The front closure of the lamp is shown at 15, exemplified as a door provided with a glass 16. The door is suitably mounted on the body, as by hinges 17, or the casing, reflector and door may be suitably connected together in other manner, so that, if it is desired to have ready access to the light-bulb, shown at 18, the front glass 16 may be removed, in order that the adjustment of the light-bulb to focus may be obtained by manual handling of the light-bulb. If, however, the adjustment of the light-bulb is to be effected from the outside 105

of the casing, the door of the lamp or its glass may, if desired, be more firmly attached to the body of the lamp.

My present invention is more particularly directed to adjusting the position of the light-bulb from the outside of the casing.

A socket-member is provided to which the electric light-bulb is arranged to be secured, this socket-member being instanced as a

10 socket-tube 21 received in a central rear aperture 22 of the reflector and a central rear aperture 23 of the lamp casing. A flange 24 extends forwardly from the casing in the space 14, and is shown on a flange-piece 25 15 rigidly secured to the casing, as by soldering. The wall of the aperture 22 is preferably strengthened by slightly turning the metal of the reflector rearwardly for forming an annular bent edge 26.

20 The socket-member has bulb attaching means at its forward end, shown as bayonet slots 27, in the wall of the tube arranged for receiving pins 28 of the plug 29 of the electric light-bulb. The rear end of the 25 socket-member is provided with connector-plug attaching means, shown as bayonet slots 30 in the wall of the tube arranged for receiving the pins 31 of the connector plug 32.

30 The socket-member is arranged to have guided movement in the flange 24 and the rear aperture of the reflector, and in my improved device this guided movement may be a rotative movement, an axial movement, 35 or a movement in a direction which is the sum of these two movements, for which purpose the outer periphery of the socket-member and the inner faces of its guiding members are annular. A resilient member

40 is provided, with relation to which said socket-member has movement, said resilient member and said socket-member having coacting surfaces arranged for permitting all said movements and for holding said socket-member in adjusted positions. Thus the 45 socket-member is provided with protuberances 19 and depressions 20, the depressions extending in a plurality of directions across each other for forming the protuberances.

50 The coacting member for said surface is shown as a shoe 33 which is received through an opening 34 in the flange 24, and has an inner end provided with protuberances 36 and depressions 37, coacting with the 55 protuberances and the depressions on the socket-member. The shoe is mounted on a spring 38, shown as a band spring curved to be received about the flange, the band preferably extending more than half way around

60 the flange, so that it will be retained on said flange by spring pressure and arranged to be releasably received thereabout. It preferably has an outwardly turned end 39 for permitting the spring to be readily pushed 65 about the flange.

The spring urges the shoe 33 toward the socket-member for continuously maintaining resilient contact between said shoe and said socket-member. A plurality of protuberances on one of said coacting position-maintaining parts is preferably received in a plurality of the depressions of the other of said parts, so as to securely maintain said parts in relatively adjusted relations.

A terminal post 41 is arranged to be 75 pressed toward the light-bulb by a spring 42, this post being shown as a sleeve slidable in a bushing 43 suitably rigidly secured in an insulating washer 44 rigidly positioned in the socket-member. A terminal post 45 is 80 provided for the connector-plug and is arranged to be normally pressed toward the connector-plug by a spring 46, the terminal post 45 being slidable in the terminal post 41. The plug of the lamp-bulb is arranged 85 to be received in its socket, so that its terminal 47 will make electric connection with the post 41, and the connector-plug is arranged to be received in the outer end of the socket-member, so that its terminal 48 will 90 make electric connection with the post 45, the posts 41 and 45 maintaining electric connection with each other, and the springs 42 and 46 urging said posts into electric 95 contact with the terminals of the light-bulb and connector-plug respectively.

In attaching the light-bulb or the connector-plug to the socket-member, sufficient pressure must be exerted thereupon manually to compress the respective springs 42 and 46, in order that the pins on said respective plugs may be received in the side slots of the respective bayonet slots of the socket-member. The holding properties of the spring 38 and the coacting maintaining 100 faces of the positioning means for the socket-member may not be sufficient to counteract the force exerted in so connecting the light-bulb or connector-plug with the socket-member. The socket-member is therefore likely 105 to be manually pushed endwise in either direction respectively by the bulb or the connector-plug.

It is desirable to limit this axial movement of the socket-member in both directions so as to maintain the socket-member in its guides. In order to limit the movement of the socket-member I provide the same with an outwardly struck lip 49, located in the space between the casing and reflector, 110 the lip coacting respectively with the flange 24 extending from the case and the edge 26 of the reflector for limiting endwise movement of the socket-member.

I prefer to provide the edge 26 with one 115 or more recesses 51 in which the lip 49 is received when the socket-member is pushed forwardly in attaching or detaching the connector-plug, the rotation of the socket-member being prevented when the lip is 120

125 130

received in one of the recesses 51, so that axial and rotative force may be manually applied to the connector-plug for forcing its pins into or out of bayonet connection at the outer end of the socket-member.

The inner end of the flange 24 is also preferably provided with one or more similar recesses 52, in one of which the lip 49 is received when the socket-member is manually pushed rearwardly during attachment or detachment of the light-bulb to the socket-member, whereby the axial movement of the socket-member is limited and its rotative movement prevented during such attachment or detachment.

A slight reverse axial movement of the socket-member by pulling on the light-bulb or the connector-plug after the same are seated, will draw the lip out of the recess 20 into which it has been forced for again permitting the turning of the socket-member.

If desired, the lip may at its forward and rear ends be made tapering, as shown at 53, 54, whereby a wedging of the socket-member in its guide against either the wall of the annular edge 26 or the wall of the flange 24 may be effected upon axial movement of the socket-member, for limiting said axial movement and also preventing its rotative movement during attachment or detachment of the light-bulb or connector-plug, this wedging action taking place between said lip and any point in the circumference of said walls of said edge and flange respectively.

The axial, rotary, and combined axial and rotary movements obtainable in my improved device afford ease of manual manipulation of the light-bulb, the parts being so arranged however as to afford great resistance to unintentional shifting after adjustment.

The arrangement of my improved device whereby provision is made for imparting an axial movement, and a rotative movement, and a movement which is the sum of both said movements, to the light-bulb, that is to say, for imparting movements to said light-bulb in any direction along or about the line of the principal axis of the reflector, enables me to adjust the light-bulb in such manner as to accommodate the position of the filament in the light-bulb to the reflector for placing the filament, for instance, in a line up or down or sidewise, or presenting any portion of the filament toward any portion of the reflector for producing the best light results, and for adjusting the filament into the focus of the reflector, whereby the most effective results may be obtained.

Having thus fully described my invention, what I claim as new and desire to secure by Letters Patent, is:

1. In an electric lamp, the combination of a casing, a reflector, a socket-member in the line of the principal axis of the reflector

having an outer socket for a connector-plug opening outwardly at said casing and an inner socket for a light-bulb opening inwardly at said reflector, and position-retaining means acting resiliently on said socket-member, whereby said socket-member is arranged to be manually moved from either end in any direction along or about said line of the principal axis of the reflector and said position-retaining means remaining automatically active for retaining said socket-member in adjusted positions.

2. In an electric lamp, the combination of a casing, a reflector, a socket-member in the line of the principal axis of the reflector having a socket at each of its ends, a plug for each of said sockets, spring-pressed connecting means between said socket-members and each of said plugs arranged to be connected by axial and rotary movements of said plugs, position-retaining means acting resiliently on said socket-member, whereby said socket-member is arranged to be manually moved in any direction along or about the line of the principal axis of the reflector and said position-retaining means remaining automatically active for retaining said socket-member in adjusted position, and stopping means limiting movements of said socket-member in the directions of said axial and rotary movements of said plugs during connecting of said plugs.

3. In an electric lamp, the combination of a casing and a reflector constituting lamp-elements, said casing and reflector having a space therebetween, a socket-member having guiding means in the space between said lamp-elements, said guiding means comprising a flange extending parallel to the line of the principal axis of said reflector into said space from one of said lamp-elements, said socket-member provided with a connector-plug socket at its casing end and with a light-bulb socket at its reflector end, and resiliently acting position-retaining means in said space, said last-named means and said socket-member provided with coacting retardent surface-formation extending in a plurality of directions for movement of said socket-member axially, rotatively, or in a direction which is the sum of said axial and rotative movements and automatically retaining said socket-member in adjusted positions.

4. In an electric lamp, the combination of a casing and a reflector constituting lamp-elements, said casing and reflector having a space therebetween, a socket-member having guiding means in the space between said lamp-elements, said guiding means comprising a flange extending in the line of the principal axis of the reflector into said space from one of said lamp-elements, said socket-member provided with a socket for a connector-plug at its casing end and with

- a socket for the plug of a light-bulb at its reflector end, resiliently acting position-retaining means in said space, said last-named means and said socket-member provided with coacting retardant surface-formation extending in a plurality of directions for movement of said socket-member axially, rotatively, or in directions which are the sum of said axial and rotative movements and automatically retaining said socket-member in adjusted positions, and means for limiting axial and rotative movements of said socket-member for attachment of said plugs.
- 15 5. In an electric lamp, the combination of a casing and a reflector constituting a pair of lamp-elements having a space therebetween, a flange extending into said space from one of said lamp-elements in the line 20 of the principal axis of the reflector, a socket-member received in said flange, a resilient position-retaining means, said last-named means and said socket-member provided with coacting retardant surface-formation extending in a plurality of directions for movement of said socket-member axially, rotatively, or in directions which are the sum of said axial and rotative movements and automatically retaining said 25 socket-member in adjusted positions, and a stop on said socket-member having a tapered end coacting with one of said lamp-elements.
6. In an electric lamp, the combination of a casing and a reflector constituting a pair 30 of lamp-elements having a space therebetween, a flange extending into said space from one of said lamp-elements in the line of the principal axis of the reflector, a socket-member guided therein and provided 35 with a socket at its casing end for a connector-plug and with a socket at its reflector end for the plug of a light-bulb, said flange provided with an aperture, and a band-
- 40

spring provided with a shoe, said band-spring removably received about said flange 45 with said shoe located in said aperture, said socket-piece and shoe provided with coacting retardant surface-formation extending crossingly in a plurality of directions for movement of said socket-member in all directions along and about said principal axis of the reflector and for continuously urging coaction between said coacting retardant surface-formation.

7. In an electric lamp, the combination of 55 a casing, and a reflector constituting a pair of lamp-elements having a space therebetween, a flange extending into said space from one of said lamp-elements in the line of the principal axis of the reflector, a 55 socket-member guided therein and provided with a socket at its casing end for a connector-plug and with a socket at its reflector end for the plug of a light-bulb, said flange provided with an aperture, and a band- 60 spring provided with a shoe, said band-spring removably received about said flange with said shoe located in said aperture, said socket-piece and shoe provided with coacting retardant surface-formation extending 70 crossingly in a plurality of directions for movement of said socket-member in all directions along and about said principal axis of the reflector and for continuously urging coaction between said coacting retardant surface-formation, and said socket-member provided with a stop coacting with the end 75 of said flange and the other of said lamp-elements.

In testimony whereof, I have hereunto 80 signed my name in the presence of two sub-scribing witnesses.

CHARLES HARRY FISCHER.
